(57) **CLAIM**

We claim the ornamental design for an agility mat, as shown and described.

DESCRIPTION

FIG. 1 is a front elevational view of the agility mat.

FIG. 2 is a back elevational view of the agility mat shown in FIG. 1.

FIG. 3 is a right-side view, which is identical to the left-side view, of the agility mat shown in FIG. 1; and,

FIG. 4 is a front view, which is identical to the rear view, of the agility mat shown in FIG. 1.
